ROTARY DUPLICATING MACHINE

Roscoe R. Rockwell, Milwaukee, Wis.

Application December 6, 1939, Serial No. 307,843

2 Claims. (Cl. 91—51)

This invention relates to duplicating machines of the liquid or spirit type, in which a moistened worksheet is impressed upon a cylinder provided with a master copy, containing subject matter produced in soluble copy ink.

One of the greatest difficulties encountered in machines of the foregoing type is to obtain proper uniform moistening of the worksheet, in order to produce uniform copies of desired impression.

In co-pending application for Letters Patent, Serial No. 271,971, filed May 5, 1939, the foregoing difficulty has been overcome to a large extent by intermittent operation of a roller moistening mechanism, incorporating a hard squeegee roll for distributing and removing excess fluid from the moistening roll. However, in actual practice it developed that from a manufacturing standpoint it was practically impossible to obtain perfect contact between two hard rolls sufficient to uniformly remove excess fluid from the surface of the moistening roll, thus causing greater moistening of the worksheet in certain areas, resulting in deeper impressions at those points to produce non-uniform copies.

Also, because of the intermittent drive of the moistening roll, it was found that during the initial operation of the roll, it failed to sufficiently moisten the worksheet, with the result that the leading end of the sheet received a lighter impression than the following portion, making the copy non-uniform.

Several theories may be advanced in explanation of the foregoing result, one being that rapid starting of the moistening roll has a tendency to break the capillary attraction between the fluid and surface of the roll, with the result that insufficient moisture is retained by the surface of the moistening roll for transmission to the worksheet until such time as the fluid starts to flow in the direction of movement of the roll.

Also, it might be said that the moistening roll must be rotated a substantial distance before sufficient fluid is accumulated at the point of contact between the moistening roll and squeegee roller, to insure sufficient retention of moisture on the surface of the moistening roll. At any rate, the fact remains that in the use of hard moistening and squeegee rollers, insufficient moisture is transferred to the worksheet during initial operation of the moistening mechanism.

Therefore, the present invention has primarily for its object to overcome the foregoing objections by the provision of a moistening device of the driven type, consisting of two rollers con-

tacting one another throughout the entire length, one of said rollers being formed of impervious yieldable material, such as rubber, synthetic rubber, or similar composition, whereby the rolls cooperate to provide uniform distribution of the fluid, and elimination of excess fluid.

Incidental to the foregoing, a more specific object of the invention is to provide a moistening mechanism of the character described comprising a hard moistening roll partially submerged in fluid, and in contact with a squeegee roll formed of yieldable impervious material, and having a surface characterized by minute pockets capable of retaining sufficient fluid to insure proper uniform moistening of the moistening roll at various speeds of rotation, and particularly upon initial starting of the moistening device.

With the above and other objects in view which will appear as the description proceeds, the invention resides in the novel construction, combination, and arrangement of parts, substantially as hereinafter described, and more particularly defined by the appended claims, it being understood that such changes in the precise embodiment of the herein disclosed invention may be made as come within the scope of the claims.

In the accompanying drawing is illustrated one complete example of the physical embodiment of the present invention, constructed according to the best mode so far devised for the practical application of the principles thereof.

In the drawing:

The single illustration in the accompanying drawing is a fragmentary longitudinal section through a duplicating machine embodying the present invention, which may be incorporated in machines of various structures without affecting the operation or principles thereof.

Referring now more particularly to the accompanying drawing, the numeral 1 designates generally a casing consisting of spaced side walls 2 connected by table 4 for reception of a stack of worksheets separately fed, either manually or automatically, to the moistening mechanism 5 comprising the subject matter of the present invention.

Journaled within the casing, and continuously driven by suitable means, either manual or power-actuated, is a platen cylinder 6 for reception of a master copy. A pressure roll 7, in contact with the platen cylinder, serves to impress the worksheets against the master copy, and draw the same through the moistening

mechanism 5, subsequent to initial operation of the moistening mechanism, as will be herein-after described. An inclined plate 8 secured to the end wall 3, and terminating adjacent the platen cylinder, receives the worksheets and delivers the same to a stack or support (not shown) conveniently located with reference to the casing.

The moistening mechanism 5 comprises a trough 9 suitably mounted within the housing 1, adjacent the inner end of the supporting table 4, for the reception of fluid to be transmitted to the worksheet for dissolving the ink contained on the master copy. Journalized in end brackets 10 carried by the trough 9, and positioned within the trough for partial submersion in the fluid contained therein, is a moistening roll 11, which contacts a squeegee roll 12, slidably journaled in brackets 10, and yieldably held against the moistening roll by suitable springs 13. Positioned above the moistening roll 11, and in contact therewith is a frictional feed roller 14 journaled in the end brackets 10, and provided at one end with a disc 15, preferably formed of fibre or other non-metallic material, and operatively engaged by a tooth sector 16 rotatable with the platen cylinder 6.

A hood 17 carried by the side walls 2 of the casing extends over the moistening mechanism to protect the same against dirt, and also prevent accidental insertion of the operator's hand into the moistening rolls. The forward wall 18 of the hood is inclined downwardly, and terminates in a lip 19, that cooperates with the inner end of the supporting table 4, to form a throat for guiding worksheets to the bight between the moistening roll 11 and the feed roller 14.

In that form of the invention illustrated, the moistening roll 11 is preferably formed of hard, smooth material, either metal or suitable composition, while the squeegee roll 12 is formed of impervious yieldable material, such as rubber, synthetic rubber, or composition having similar characteristics, the surface of the roll being slightly rough in its finish to provide minute pockets for receiving and retaining moisture as a result of its contact with the moistening roll 11.

From the foregoing explanation considered in connection with the accompanying drawing, it is thought that the operation of the invention will be readily apparent, in that the worksheets are fed to the bight formed between the moistening roll 11 and the feed roller 14. The mechanism is so timed as to cause the sector 16, which rotates with the platen cylinder 6, to engage the disc 15 and rotate the feed roller 14, which operation delivers the worksheets to the platen cylinder 6, upon which the sheets are impressed by the pressure roll 7 to reproduce the subject contained on the master copy.

It might also be explained that the intermittent drive of the feed roller 14 is so timed that the roller is operated only when in contact with a worksheet. Consequently, no moisture or fluid from the roll 11 is transmitted to the feed roller

at any time. Obviously, because of the pressure of the feed roller 14 upon the moistening roll 11, drive will be imparted to the latter upon rotation of the feed roller, and during rotation of the moistening roll, fluid is picked up from the trough and carried to the squeegee roll 12, that serves not only to uniformly distribute fluid over the surface of the moistening roll, but also remove through squeezing action excess fluid.

As heretofore explained, it was found in the use of a hard squeegee roll, that it was practically impossible to obtain a perfect contact between the squeegee roll and the moistening roll, and also it was impossible to retain sufficient moisture upon the surface of the moistening roll during its initial operation. The present squeegee roll formed of yieldable impervious material entirely overcomes the foregoing objections, in that its yieldability insures perfect contact regardless of irregularities in either roll; and at the same time, because of the character of the surface of the squeegee roll, sufficient fluid is retained by it to insure proper moistening of the surface of the roll 11 at all times during its rotation, and at variable speeds.

In other words, the minute pockets present in the surface of the squeegee roll are capable of retaining and transmitting sufficient moisture to the surface of the roll 11 at the point of contact with the squeegee roll, which would not be true of hard rolls designed to provide a flat surface of contact.

It will be apparent from the foregoing that exceedingly simple and efficient means have been provided for moistening worksheets of a fluid duplicating machine, whereby the amount of moisture can be accurately controlled and evenly distributed over the entire work sheet to obtain a uniform and clear copy.

I claim:

1. In a duplicating machine of the class described, a sheet moistening mechanism comprising, a fluid trough, a moistening roll of hard, smooth material positioned in said trough and partially submerged in the fluid, a squeegee roll engaging said moistening roll and formed of yieldable impervious material having minute pockets in its peripheral surface, and a frictional roller engaging said moistening roll for feeding sheets over the same.

2. In a duplicating machine of the class described, a sheet moistening mechanism comprising, a fluid trough, a moistening roll of hard, smooth material positioned in said trough and partially submerged in the fluid, a squeegee roll engaging said moistening roll and formed of yieldable impervious material having minute exposed pockets in its peripheral surface, a frictional feed roller engaging said moistening roll to feed sheets over the same, and means for intermittently rotating said feed roller only when the same is in engagement with a work sheet.

ROSCOE R. ROCKHILL.
